UNITED STATES PATENT OFFICE

104,300

DESIGN FOR A CONTAINER

Sylvan M. Wolfsheim, Buffalo, N. Y., assignor to Wolfsheim & Sachs, Inc., Buffalo, N. Y., a corporation of New York

Application March 12, 1937, Serial No. 68,142

Term of patent 7 years

To all whom it may concern:

Be it known that I, Sylvan M. Wolfsheim, a citizen of the United States, residing at Buffalo, in the county of Erie and State of New York, have invented a new, original, and ornamental Design for a Container, of which the following is a specification, reference being had to the accompanying drawing, forming a part thereof.

Figure 1 is a plan view of the container embodying my new design, showing the same in a closed position;

I claim:

The ornamental design for a container, as shown.

SYLVAN M. WOLFSHEIM.
